UNITED STATES PATENT OFFICE.

ARTHUR FORD, OF WELLINGTON, TEXAS.

AUTOMATIC LIQUID-FUEL REGULATOR FOR STEAM-GENERATORS.

1,007,413.

Specification of Letters Patent. Patented May 19, 1914.

Application filed May 13, 1913. Serial No. 767,349.

To all whom it may concern:

Be it known that I, ARTHUR FORD, a citizen of the United States, residing at Wellington, in the county of Collingsworth and 5 State of Texas, have invented new and useful Improvements in Automatic Liquid-Fuel Regulators for Steam-Generators, of which the following is a specification.

This invention is an improved automatic liquid fuel feed regulator for steam generators especially adapted for use in connection with steam generators in which liquid hydrocarbon or gas is used as fuel, the object of the invention being to provide an improved mechanism of this kind which when properly adjusted will automatically regulate the supply of liquid fuel to the burners of the furnace according to the pressure of the steam in the boiler and thus serve to automatically keep the steam at any pressure desired and prevent the waste of fuel and also prevent an insufficient quantity of fuel from being supplied to the furnace.

The invention consists in the construction, combination and arrangement of devices hereinafter described and claimed.

In the accompanying drawings: Figure 1 is an elevation of a liquid fuel feed regulator constructed in accordance with my invention, showing the same arranged in operative relation to a steam boiler and its furnace. Fig. 2 is a detail elevation of the improved automatic liquid fuel feed regulator, on a larger scale, and with the cylinder 30 of the steam pressure actuated mechanism in section. Fig. 3 is a detail transverse sectional view on the plane indicated by the line *a—a* of Fig. 2. Fig. 4 is a detail horizontal sectional view of the rocker segment 40 on the plane indicated by the line *b—b* of Fig. 2 and showing the valve actuated lever in plan.

For the purposes of this specification, I show in Fig. 1 of the drawings a steam boiler at 1, its furnace at 2 and a tank or reservoir for liquid hydrocarbon for use as fuel to be burned by the burners of the furnace at 3. Where the invention is for use in connection with a furnace in which gas is burned as a fuel, the reservoir 3 will be replaced by a suitable gas bell or a supply pipe leading from an ordinary gas system will be utilized.

In accordance with my invention, I provide the fuel supply pipe 4, which leads from the source of liquid hydrocarbon or

gas to the burner or burners in the furnace with a suitable regulating valve 5 which is here shown as a vertically movable gate valve. This valve is connected by a rod 6 to one end of a valve actuating lever 7, the fulcrum of which is indicated at 8 and the said lever has a handle 9 at its outer end and is provided at a suitable distance from its outer end with a web or tooth 10 for engagement with anyone of a series of teeth 11 with which a rocker segment 12 is provided.

The lever 7 is elastic, being, in practice, preferably made of steel and serves by its own spring action to keep its tooth 10 in engagement with a tooth 11 of the rocker segment when the lever is adjusted on the rocker segment. The pivot of the rocker segment is coincident with the fulcrum 8 of the lever and, in practice, a suitable standard or other support 13 is provided from which the common pivot or fulcrum of the valve actuating lever and the rocker segment projects. I also provide a steam pressure actuating mechanism which is here shown as comprising a cylinder 13 connected to the steam space of the boiler by a pipe 14 which discharges into the bottom of the cylinder, and a piston 15 in the cylinder and which is adapted to be moved by the pressure of steam in the cylinder below the piston. At the upper end of the cylinder is a pair of vertically arranged threaded adjusting stems or standards 16 on which a bar or plate 17 is fitted for vertical adjustment, the said bar or plate being provided with unthreaded openings through which the threaded adjusting stems or guides extend. A pair of adjusting nuts 18 are also provided which engage the threaded adjusting stems, bear on the upper side of the bar or plate 17 and enable the latter to be vertically adjusted, as will be understood. A tension spring 19 is also provided, which is here shown as a coiled extensible spring arranged around the piston rod 20 which extends upwardly from the piston, the lower end of the said spring bearing on the piston and its upper end bearing against the under side of the bar or plate 17. This spring 19 is to counteract the pressure of steam in the cylinder below the piston.

The piston rod 20 operates in an opening in the center of the bar or plate 17 and is connected by a rod 21 to the lower corner of the rocker segment 12, the said rod being

pivots attached to the piston rod and also to the rocker segment. The tension of the counteracting spring 19 may be varied by adjusting the plate or bar 17 according to the desired pressure in the boiler and the valve actuating lever should be adjusted appropriately to the rocker segment.

In the operation of my improved fuel feed regulator the valve 5 is open until the desired pressure of steam in the boiler is obtained, the counteracting spring 19 serving to depress the piston 15 and to hold the latter in depressed position in the cylinder. When, however, the pressure of steam in the boiler exceeds that desired, the piston 15 is moved upwardly in the cylinder 13 against the tension of the spring 19, thus causing the rocker segment to be partly turned and the valve actuating lever to move correspondingly with the rocker segment and, hence, partially close the valve 5 to the required extent to so diminish the supply of liquid fuel to the burners as to prevent steam from being generated at excess pressure. As soon as the steam pressure becomes reduced, the counteracting spring 19 will correspondingly depress the piston 15 and thus cause the regulating valve 5 to be more widely opened and thus supply an increased quantity of fuel to the burners in the furnace. Hence, my liquid fuel feed mechanism is automatically operated and controlled by

the steam pressure in the boiler and by the coaction of the counteracting spring, excess steam pressure in the boiler is avoided and an economy of fuel effected.

While I have herein shown and described a preferred form of my invention, I would have it understood that changes may be made in the form, proportion and construction of the several parts without departing from the spirit of the invention and within the scope of the appended claim.

I claim:—

In combination with a steam generator and a burner, a valve to regulate the supply of fluid fuel to the burner, a rocker element having a segmental rack, a lever to engage the segmental rack, said rocker element and lever having a common pivot, a pressure actuated mechanism including a cylinder having steam connection with the boiler and a piston in the cylinder and movable in one direction by the steam pressure, a counteracting spring to move the piston in the reverse direction, a rod projecting from the piston and a pitman pivotally connected to the rocker element and to the piston rod.

In testimony whereof I affix my signature in presence of two witnesses.

ARTHUR FORD.
